UNITED STATES PATENT OFFICE

ARTHUR E. HOWELL, OF BROOKLYN, NEW YORK, ASSIGNOR TO UNDERWOOD ELLIOTT FISHER COMPANY, OF NEW YORK, N. Y., A CORPORATION OF DELAWARE

TYPEWRITING MACHINE

Application filed November 24, 1928. Serial No. 321,535.

This invention relates to revoluble platens for typewriting machines.

In this invention the sound vibrations caused by type-impacts are diminished and largely absorbed by continuous flexible tubes of small diameter, which run longitudinally near the surface of the platen. These tubes weaken, distribute and break up the vibrations, so that noises caused by the latter are deadened. This invention makes possible two highly desirable results, namely: noiseless operation and clear printing. Furthermore, the platen is simple, lasting, efficient and inexpensive.

In the construction illustrated, the hard outer wearing shell is made as usual and common, of vulcanized rubber composition.

In order to help deaden the sound of the type-impact on the outer shell, it is mounted on an inner sleeve made of material which is softer and more resilient. In this sleeve there are embedded before vulcanization, a series of flexible tubes of small diameter, which lie side by side and run longitudinally for nearly the full length of the platen. These tubes are preferably of tightly coiled aluminum wire, which is very light and also absorbs vibrations readily, and also because of its flexibility reduces the noise. Due to the great length of wire in each tube, the vibrations absorbed will follow the coils over long distances until they are weakened and become inaudible.

The aforementioned inner sleeve is drawn over a hollow wooden core which serves as a support, and also has sound-deadening qualities. The center of said core is bored out to make it lighter, and also to provide a dead-air space, which still further reduces noise. To further minimize the latter, the inner surface of the core is covered with heavy paper, which is attached with adhesive. When the platen has been built up, the usual end plates are attached for supporting it in the carriage.

The above construction has been found highly efficacious in deadening sounds. Each of its cylindrical elements are of sound-absorbing material. Furthermore, by using several differing materials, each has a different structure, which does not transmit sound-waves with uniformity, for the reason that sound-waves are bent, broken and impeded. The sounds therefore are successively decreased by each cylindrical element through which they are inwardly transmitted or absorbed, and the noise of typing is minimized.

Through the use of tubes in the inner sleeve, a more rigid support is afforded to the outer sleeve when struck by the type, which insures the clear type-impressions. Because the tubes support the structure of the inner sleeve, a softer material can be used therein, which has the advantage of being more highly sound-deadening. In more rigidly supporting the hard outer shell, the tubes must of necessity receive a greater number of vibrations. These are readily absorbed, however, by the many feet of wire in the coils of the tubes, whereby the tubes set up an advantageous resistance, and concurrently absorb the greater number of vibrations so set up.

In accomplishing the sound-deadening, as explained, the prime essential is the tubes. In so long as they are incorporated near the surface of the platen, their immediately adjacent structure is not so important. For this reason an alternative construction is shown in addition to the one above described. Such alternate construction is illustrated by Figures 3 and 4 and has three elements in common with the other, namely, a hard shell, a wooden core and a paper-lining. In the one form of construction the tubes are vulcanized into a composition-sleeve, and in the other the tubes interlie layers of felt or other sound-deadening material, which, taken as a unit, may also be considered as a sleeve.

Each form of construction has an advantageous use, as becomes apparent. When a typewriter is used for manifolding a comparatively few copies, the force of the type-blows is comparatively light, in order to save the type. Under such conditions little compression has to be resisted by the coiled wire tubes, and very little rigidity is needed therein. For this reason a fine aluminum wire may be used for lightness, and because it is not adversely affected by the heat necessary to vulcanize the sleeve.

When a great number of sheets has to be manifolded, the type-impact is harder, in which case more resistance is required in the walls of the coiled wire tubes in order to support the outer shell against the type-blows. Under these conditions it is advisable in forming the tubes, to use steel or other hard wire.

An advantage of having the flexible tubes contiguous is, that more tubes can be used, and the vibrations received by any one tube are not alone carried along its own coils, but will also be transmitted to adjacent ones. The vibrations therefore will radiate from the point of type-impact, and will be more quickly absorbed and weakened to avoid noise.

Another sound-deadening feature resultant from the use of tubes, is the dead-air space formed by, and within, each tube, which is hermetically sealed at each end for this purpose. The confined air within said space has sound-deadening properties. Where fine aluminum wire is used, the tubes will not readily become permanently distorted under compression, and will not lose their usefulness.

While the above description pertains particularly to tubes made of coiled wire, it is not wished to limit this invention entirely to the use thereof. This because experiment has shown, that tubes of other material and form will also deaden sound very appreciably, when used in the manner shown and described.

Other features and advantages will hereinafter appear.

In the accompanying drawings,

Figure 1 is an enlarged cross-sectional view of a revoluble platen, and shows the tubes embedded in vulcanized soft rubber composition.

Figure 2 is a partial longitudinal sectional view of the platen shown in Figure 1.

Figure 3 is a cross-sectional view of a revoluble platen, and shows the tubes interlying layers of felt or other sound-deadening material.

Figure 4 is a partial longitudinal sectional view of the platen shown in Figure 3.

Referring to the drawings, 10 is a comparatively hard outer wearing sleeve or shell of vulcanized rubber composition, against

which the types 11 will contact. The sleeve 10 is tightly superimposed on an inner sleeve 12, which is also of vulcanized rubber composition, but which is made softer and more resilient. Embedded in the inner sleeve 12 are contiguous flexible wire tubes 13 which are slightly shorter than the sleeve and have thin end walls 14. The latter confine the air within the cavities formed by the tubes, and provide cushioning and sound-deadening features.

The two sleeves 10 and 12 are tightly mounted on a wooden core 15, which is bored out to leave a space 16. The circumferential wall of said space is covered with paper 17. The latter can be held against the wall by adhesive, or can be a tube which is forced into said space. Through the space 16 there will normally run a shaft 19, which, by means of end plates 18, supports the platen in a typewriter-carriage. Said end plates have a tight fit on said shaft, to seal said space 16, and minimize the escape of sound-waves therefrom. The end plates 18 also have set screws 19^a, and countersunk screws 20, which attach said plates to said wooden core.

In the modified form of construction shown by Figures 3 and 4, all the parts are the same as shown in Figures 1 and 2, with the exception of the inner sleeve 12. In lieu of the latter there can be used a different form of sleeve, having layers 21 and 22 of sound-deadening material, such as felt, which are concentric, and have the tubes 13 interlying the same. This modified construction can be applied in two ways. In the one, a layer 21 is attached by adhesive to the wooden core 15, after which, adhesive is applied to the outside surface of said layer. The tubes are then applied and will adhere to the surface. Adhesive is next applied over the tubes, which are then covered by the layer 22. When the adhesive has dried, the outer shell is drawn over the whole, and the end plates are attached.

Another method of assembling the modified form of platen is to build up the two layers and interlying tubes as a unit. This is accomplished through the use of a mandrel, around which a layer, the tubes and another layer are respectively applied, and which are unified by adhesive on adjacent surfaces. When the adhesive is dry, the built-up sleeve is removed from the mandrel, and can be slipped over the wooden core. Before placing, however, the core can be coated with a thin layer of adhesive, which, when dry, will hold the sleeve in place. As in the first method, the outer shell is then drawn over the inner sleeve, and the end plates are attached.

In using the modified form of construction, a space is left at each end of the tubes, which, as previously mentioned, are slightly shorter than the sleeve. In order to confine the air

within the cavities of the tubes, and thereby maintain an air-cushion, said spaces are sealed with sound-deadening material 23. The latter can be a viscous material that will dry out and become resilient, or it may be a ring of sound-deadening material, such as felt.

In portable typewriters, where lightness and compactness are requisites, the platens 10 have smaller diameters than those of the standard models. Also as the portable models are not ordinarily used for manifolding a large number of copy-sheets, it is possible to use a platen having a relatively soft working 15 surface. It is a feature of this invention that it is particularly fitted to successfully aid just such conditions, as the wire helices afford a firm support against the type-blows, but are yieldable under said blows.

20 In using this invention for portable typewriters, it may be applied to the platen by the two methods aforementioned, or still another modification may be employed. In the latter the core, while being of smaller diameter, can 25 also have a central space of relatively large diameter, which will appreciably lighten the core. In order to maintain the smaller finished diameter of the platen, the composition covering will be made thinner. This thinner 30 covering can, in fact, be made in one thickness or sleeve, which has the tubes embedded therein.

In using a thin sleeve, as described, the small mass of material in the walls will not 35 effectively deaden all the sounds of type-impacts. This condition is ameliorated to some extent by the use of the softer material in the sleeve, which, however, would ordinarily be inimical to clear type-impressions. The flexible 40 tubes featured in this invention stiffen this softer material, and therefore insure the clearer impressions. At the same time the coils of the tubes, and the dead-air spaces therein absorb and deaden the sounds. Furthermore, through increasing the dead-air 45 space within the core, more sound-waves are absorbed, and noise is still further reduced. This invention therefore makes possible the use of a small light platen, which is still highly effective in deadening sounds.

Variations may be resorted to within the scope of the invention, and portions of the improvements may be used without others.

Having thus described my invention, I 55 claim:

1. In a typewriter-platen, a wooden core which is hollow, end plates attached to said core for mounting the same on a shaft, paper attached to the inner surface of said core, a resilient sleeve on said core, small tubes extending longitudinally of the platen and forming a circular row in said sleeve, and a relatively hard resilient outer sleeve which tightly fits over the other sleeve.

2. In a typewriter-platen, a wooden core

which is hollow, end plates attached to said core for mounting the same on a shaft, a sleeve on said core, said sleeve of vulcanized rubber composition, which is resilient and tightly embraces the core, tubes embedded in said sleeve, said tubes being contiguous and extending longitudinally of said sleeve, and a relatively hard outer sleeve which tightly fits over the other sleeve.

3. In a typewriter-platen, a wooden core which is hollow, end plates attached to said core for mounting the same on a shaft, paper attached to the inner surface of said core, a sleeve of resilient sound-deadening material which tightly encompasses said core, contiguous tubes embedded in said sleeve and extending longitudinally thereof, said tubes being of coiled wire, the tubes not extending to the ends of said sleeve, and a relatively hard outer sleeve of vulcanized rubber composition which is tightly fitted over the other sleeve.

4. In a typewriter-platen, a wooden core which is hollow, end plates attached to said core for mounting the same on a shaft, paper attached to the inner surface of said core, a sleeve of resilient sound-deadening material which tightly encompasses said core, contiguous tubes embedded in said sleeve and extending longitudinally thereof, said tubes having resilient walls, the tubes not extending to the ends of said sleeve, and a relatively hard outer sleeve of vulcanized rubber composition which is tightly fitted over the other sleeve.

5. In a typewriter-platen, a wooden core which is hollow, end plates attached to said core for mounting the same on a shaft, paper attached to the inner surface of said core, a resilient sleeve on said core, another sleeve tightly superimposed thereon and forming an outer shell, the latter of relatively hard vulcanized rubber composition, and contiguous tubes embedded in the first-mentioned sleeve, said tubes having resilient walls and forming cavities which are sealed by the surrounding material, said sealed cavities functioning as air cushions to absorb shocks when said outer shell is struck.

6. In a typewriter-platen, a wooden core which is hollow, end plates attached to said core for mounting the same on a shaft, a resilient sleeve on said core, another sleeve tightly superimposed thereon and forming an outer shell, the latter of relatively hard vulcanized rubber composition, and contiguous tubes embedded in the first-mentioned sleeve, said tubes having resilient walls and forming cavities which are sealed by the surrounding material, said sealed cavities forming dead air spaces, to absorb vibrations and deaden noise when said outer shell is struck.

7. In a typewriter-platen, a wooden core which is hollow, end plates attached to said core for mounting the same on a shaft, paper

- attached to the inner surface of said core, a resilient sleeve on said core, another sleeve tightly superimposed thereon and forming an outer shell, the latter of relatively hard vulcanized rubber composition, and contiguous tubes embedded in the first-mentioned sleeve, said tubes having resilient walls and forming cavities which are sealed by the surrounding material, said sealed cavities functioning as compression-chambers, wherein the elasticity of the air compressed will help to restore said walls to normal positions after the walls have been distorted by a blow. 15. In a typewriter-platen, a wooden core which is hollow, end plates attached to said core for mounting the same on a shaft, paper attached to the inner surface of said core, contiguous tubes surrounding said core and extending longitudinally thereof, a relatively hard tightly-fitting outer sleeve of vulcanized rubber composition, and adhesive resilient material which respectively fills the interstices between said core and said tubes and between said tubes and said outer sleeve, 20 and also seals the ends of said tubes. 25. 9. In a platen for a typewriting machine, the combination of an outer sleeve or shell, a wooden core which is hollow, end plates attached to said core for mounting the same on a platen-shaft, paper attached to the inner surface of said core, a cylindrical inner sleeve which tightly fits between said shell and said core, said inner sleeve having interior and exterior circumferential walls of resilient sound-deadening material and having interlying contiguous tubes running longitudinally and not quite to the ends thereof to leave annular spaces, and resilient sound-deadening material which fills said spaces. 30 35. 10. In a typewriter-platen, a core which is hollow, end plates attached to said core for mounting the same on a shaft, paper attached to the inner surface of said core, a resilient sleeve on said core, and contiguous tubes embedded in said sleeve and extending longitudinally thereof. 40 45. 11. A typewriter-platen including the combination of end plates, a wooden core which is hollow and to which the end plates are attached, paper attached to the inner surface of said core, a shaft which supports the end plates and to which the latter are fastened, a usual line-spacing mechanism attached to the shaft, a mass of resilient composite material which closely encompasses said core, and contiguous tubes embedded in said material and extending longitudinally thereof, said tubes of such diameters and so positioned radially from the shaft that each can be made to underlie a line of printing through registration with the line-spacing mechanism when typing is done on the platen. 50 55. 12. In a typewriter-platen, a wooden core which is hollow, end plates attached to said core for mounting the same on a shaft, paper attached to the inner surface of said core, a mass of resilient composite material which closely encompasses said core, and tubes embedded in said material to absorb vibrations caused by type-impacts and to deaden the sounds thereof. 60 65. 13. In a typewriter-platen, a core which is hollow, means attached to the same, for mounting said core, a mass of rubber composition encompassing said core, tubes embedded in said mass to absorb vibrations and reduce noise when the platen is struck, and a tube of fibrous material within said core to further deaden said noise. 70 75. 14. In a typewriter-platen, a wooden core which is hollow, end plates attached to said core for mounting said core on a platen-shaft, a tube of fibrous material engaging the inner walls of said core, rubber composition encompassing said core, and contiguous tubes embedded in said rubber composition to absorb vibrations and deaden sound when the platen is struck, said contiguous tubes being near the surface of the platen. 80 85. 15. A platen including a series of closely-wound flexible helices of wire extending lengthwise of the platen and closely assembled to serve as a locally-flexible tubular platen-body, a layer of soft sound-deadening material in which said helices are embedded, an outer hard wear-resisting element provided upon said layer, and a supporting core. 90 95. 16. In a typewriter-platen, a core which is hollow, means upon said core for mounting the same, a soft resilient sleeve on said core, another sleeve tightly superimposed thereon and forming an outer shell, the latter of relatively hard vulcanized rubber composition, and contiguous flexible resilient wire helices embedded in the first-mentioned sleeve. 100 105. 17. In a typewriter-platen, a core which is hollow, means attached to said core for mounting the same, contiguous tubes surrounding said core and extending longitudinally thereof, a relatively hard tightly-fitting outer sleeve of vulcanized rubber composition, and adhesive soft, resilient material which respectively fills the interstices between said core and said tubes and between said tubes and said outer sleeve. 110 115. 18. A typewriter-platen including the combination of end plates, a core which is hollow and to which the end plates are attached, means which support the end plates, a mass of resilient composite material which closely encompasses said core, and contiguous tubes embedded in said material and extending longitudinally thereof, said tubes of such diameter and so positioned that each underlies a line of printing through registration with the line-spacing mechanism when typing is done on the platen. 120 125. 19. In a typewriter-platen, a core which is hollow, means attached to said core for mounting the same, a mass of resilient com-

posite material which closely encompasses said core, and tubes embedded in said material to absorb vibrations caused by type-impacts and to deaden the sounds thereof.

8 20. In a typewriter-platen, a core which is hollow, means attached to said core for mounting it, rubber composition encompassing said core, and contiguous tubes embedded in said rubber composition to absorb vibrations and deaden sound when the platen is struck, said contiguous tubes being near the surface of the platen.
